(57) **CLAIM**

The ornamental design for a knee physiotherapy apparatus as shown and described.

DESCRIPTION

FIG. 1 is a front perspective view of a knee physiotherapy apparatus showing my new design;

FIG. 2 is a front elevational view thereof;

FIG. 3 is a back elevational view thereof;

FIG. 4 is a Right-side elevational view thereof;

FIG. 5 is a left-side elevational view thereof;

FIG. 6 is a top plan view thereof; and,

FIG. 7 is a bottom plan view thereof.

The broken lines shown in the drawings illustrate portions of the knee physiotherapy apparatus that form no part of the claimed design.
